UNITED STATES PATENT OFFICE.

WILLIAM HENRY SLAPPEY, OF ATLANTA, GEORGIA.

PLANTER.

SPECIFICATION forming part of Letters Patent No. 390,712, dated October 9, 1888.

Application filed March 16, 1888. Serial No. 267,402. (No model.)

To all whom it may concern:

Be it known I, WILLIAM HENRY SLAPPEY, a citizen of the United States, residing at Atlanta, in the county of Fulton and State of Georgia, have invented a new and useful Improvement in Planters, of which the following is a specification.

The invention relates to improvements in planters, the objects being to provide a simply-constructed and effective machine of the kind, and one that will not catch against brush or other obstructions, and can be easily handled; and it consists in the construction and novel combination of parts hereinafter described, 15 illustrated in the accompanying drawings, and pointed out in the claim hereto appended.

In the drawings, Figure 1 is a perspective view of a planter embodying the invention. Fig. 2 is a transverse section of the same 20 through the hopper. Fig. 3 is a central longitudinal section of the machine. Fig. 4 is a plan view of the wheel, eccentric, and eccentric-rod or pitman detached. Fig. 5 is a rear view of a part of the machine.

Referring to the drawings by letter, A designates the frame of the machine, consisting of a single piece of plate metal doubled on itself, as at a^2 , then extending backward and bent outward at right angles, as at a' , and then extended backward, forming the parallel side plates a a .

B is a clevis inserted into the front end of said frame and rendered vertically adjustable by means of the vertical series of openings b 35 in the clevis and the pin b' , passing through an opening in the frame and engaging any one of said adjusting-openings.

C is the furrow-opener, consisting of the blade or share E and the vertical tapped shank e, which enters and projects above the bearing D, made by bending the plates a outward at opposite points, and which is rendered vertically adjustable in said bearing by the nuts d d , respectively above and below said 45 plates a .

The share E is triangular in cross section and tapers downward from its circumferential shoulder e, that separates it from the shank e. The edge e' curves downward and rearward 50 from said shoulder to its point e^2 to facilitate motion through the soil when the latter is

rough or heavy, and its rear side, e^3 , also curves rearward and downward. The said rear side can be turned forward, and the point e^3 will then project forward and will tend to cut more 55 deeply into the soil. The side e^3 is turned to the front when the soil is light.

F is the seed-box, having its lower portion secured between the plates a near the rear end of the frame, and ff are the rearwardly-inclining handles, having their lower ends secured at opposite points to the outer sides of the plates a and their central parts secured by bolts to the seed-box at its rear upper portion. The rear edge of the seed-box is braced 60 by the metal plates $f'f'$, the lower ends of which are bolted to the inner sides of the plates a , while their upper ends are secured to the seed-box by the bolts that connect the handles thereto.

G is the evening and covering board having the sharp lower edge, which is also concave laterally to move the soil centrally as it covers, and with its inclination downward and forward. The said board is detachably secured to the shares H H by means of the brace-rods h h , which hook at their front ends into openings $h' h'$ in the side plates, a , and have their tapped rear ends passing through suitable openings in the boards and the upper 75 parts of the blades of the shares, nuts h^2 h^2 being on said tapped portions, respectively, in front of the coverer-board and behind the shares, so that the inclination of the coverer-board can be adjusted to a slight extent by 80 said nuts. The shanks of the said shares ride on the transverse upper and lower bolts II, that connect the rear ends of the plates a , having their heads on the outside of one of said plates and the nuts i i on the outside of the other 85 plate. The said bolts are tapped at both ends, pass through openings in the shanks, and have nuts i' , one each side of the shanks in order that the shares H can be adjusted, toward each other.

The shares may be reversed, and the coverer and evener board may have its inclination reversed by attaching the shares in a reversed position to the bolt i^2 , passing through the seed-box near its lower end, and to the bolt I, removed to the openings i' in the plates a .

J is the conveyer-wheel, preferably of wood,

having the rounded periphery j , and with its eye in the squared metallic center piece, j' , set transversely in the wheel. The wheel turns on the shaft j'' , which has its ends secured in 5 the side plates, a , a suitable distance in front of the seed-box.

On one side of the wheel is secured the eccentric-disk K , flanged around its outer edge and surrounded by the eccentric-ring k , to 10 which is secured in the usual manner the front end of the pitman k' . The pitman passes through a vertical slot, k^2 , in the front of the seed-box and has its upper rear end pivoted to the end of an arm, l , standing upward from 15 the oscillating shaft L , journaled in the sides of the seed-box. The shaft L has the upwardly-inclined diverging, stirring, and dispersing arms M rising from its upper surface and the sector-plate N depending from its 20 lower surface and set longitudinally edgewise.

n are triangular distributing fingers on the periphery of the sector-plate, which fingers move the seed forward and backward in the seed-box and facilitate their escape therefrom.

25 O are longitudinal doors secured to the inner surfaces of the sides of the seed-box, and made of spring-metal plate, and o are adjusting-screws passing through tapped openings in said sides and impinging on the plates,

so as to force them together when the screws 30 are moved inward, thus adjusting the width of the escape-opening P . The fingers n being united at their bases will withstand great breaking strain.

For heavy and rough usage the edge of the 35 furrow-opener is put in front, and the inclination of the coverer is reversed or inclined downward and rearward.

Having described my invention, I claim—

The combination of the main frame having 40 the side plates, $a a$, provided with openings h' near their rear ends, the transverse bolts I , inserted through the rear ends of the side plates and threaded at both ends, the shares H , having their shanks hung on said bolts I , the cover 45 secured to said shares, the adjusting and securing nuts mounted on both ends of the bolt I and bearing against both sides of each share, and the rods h , having their lower ends adjustably secured to the coverer and their upper ends engaging the openings h' , as specified.

In testimony that I claim the foregoing as my own I have hereto affixed my signature in presence of two witnesses.

WILLIAM HENRY SLAPPEY.
